United States Patent Office

Des. 186,141
Patented Sept. 15, 1959

186,141

ALPHABET FOR FORMING MONOGRAMS OR THE LIKE

William H. Meeker, Rochester, N.Y., assignor to Hickok
Manufacturing Co. Inc., Rochester, N.Y., a corporation of New York

Application January 8, 1959, Serial No. 54,075

Term of patent 14 years

(Cl. D64—16)

Fig. 1 is a top plan view of an alphabet for forming monograms or the like showing my new design;

Fig. 2 is a side perspective view of one of the letters; and

Fig. 3 is a side elevational view thereof.

I claim:

The ornamental design for an alphabet for forming monograms or the like, substantially as shown.
